UNITED STATES PATENT OFFICE.

WALTER FRANCIS GAUNT, OF BIRMINGHAM, ENGLAND.

MEANS FOR FIXING BUTTONS TO BELT-CLASPS AND TO CERTAIN OTHER ARTICLES.

1,192,414.

Specification of Letters Patent. Patented July 25, 1916.

Application filed September 3, 1914. Serial No. 860,818.

To all whom it may concern:

Be it known that I, WALTER FRANCIS GAUNT, of 12 Frederick street, in the city of Birmingham, England, a subject of the 5 King of Great Britain, have invented certain new and useful Improvements in Means for Fixing Buttons to Belt-Clasps and to Certain other Articles; and I do hereby declare that the following is a full, clear, and 10 exact description of the same.

This invention has reference to improved means for fixing military and naval buttons and ornaments to belt clasps and certain other articles such for instance as brooches, 15 waist belt plates, badges, hat pin heads, tobacco boxes, cigar ash trays, paper knife handles, swagger cane heads and other souvenir articles, and the like.

The kind of military and naval buttons 20 and other like buttons with which my invention is adapted to be used are those of the usual kind furnished with a necked attachment shank usually formed of a piece of wire which is bent into a somewhat circular 25 loop with a narrow neck, the two end portions of the wire forming the loop being closed together and forming said narrow neck close to the back of the button. In some buttons the necked shank of a sheet of 30 metal blank is pierced with one or two holes for the thread.

When a belt clasp or other said article is 35 constructed and fitted with my invention it is only necessary to place and press the button into a recess in the belt clasp or other said article, and then the button is by the special means which I provide at the back of the front plate of the said belt clasp or other article, automatically and firmly secured 40 and cannot turn in the said recess.

My invention is comprised in the improved means of securing the shank of the button to the belt clasp or other article by means of a spring member, preferably 45 formed of wire or sheet metal, the said spring clip member having two gripping arms located in relation to the slot in the belt clasp or other article, so that when the shank of the button is forced between said 50 arms the latter are sprung apart, then spring back and grip the shank preventing accidental withdrawal of the button retaining the latter from turning in its mount. For full comprehension, however, of my invention reference must be had to the accompanying drawings forming a part of this

specification, in which similar reference characters indicate the same parts, and wherein:

Figure 1 is a front elevation of a form 83 of belt clasp and mount. Fig. 2 is a sectional view of the means disclosed in Fig. 1; Fig. 3 is a front elevation and section of the improved construction of the back or cover plate illustrated separately from the belt 35 clasp and mount; Fig. 4 is a view similar to Fig. 1 with the button removed and illustrating a modified construction of spring clip member; Fig. 5 illustrates a spring clip member formed from a sheet metal blank 70 and of similar contour to the member shown in Fig. 4. Fig. 6 illustrates another modification of the spring clip member.

Referring first to Figs. 1 to 5 the front 75 plate A of the belt clasp B is stamped with a circular recess C of the proper size for the back part of the button D to fit in, and in the plate A at the center of this recess C there is a rectangular slot E of the proper size to admit of the passage of the looped shank F of the button D so that the said shank will project at the back of the slot E.

Fixed in a cavity at the back of the recessed front plate A, I provide a two armed wire or other metal clip member G the 35 spring arms G¹ of which extend across the slot E so that when the button shank F is inserted and pressed in to the slot the rounded sides of the button shank will force the two spring arms G¹ apart until, when the button D has been pressed right home into the recess C, the two arms G¹ in springing toward one another again engage with the neck F¹ of the button shank F, and thus effectively secure the button D in the recess 90 C, and owing to the flat sides of the loop shank fitting between the long sides of the slot E it is impossible for the button to turn in the recess C. The said clip member is by 95 preference made of a piece of wire bent into a partially ring like form with the end portions G¹ of the wire turned inwardly approximately parallel with and at a short distance from the diameter of the ring, the ring being soldered or otherwise fixed in the cavity A¹ at the back of the front A of the belt clasp so that the two comparatively 100 straight end portions G¹ of the wire form the spring arms of the clip as aforesaid.

The back of the cavity is closed by a cover 110 plate H formed with a domed central portion H¹ and countersunk holes H² and a de-

pression H^3 , the cover plate being secured by rivets 1 to the front plate A. The domed part H^1 of the cover plate is adapted to receive the shank F of the button, the depression H^3 being located within the free ends of the spring arms G^1 so as to form a positioning piece upon insertion of the clip G and to prevent the said clip from moving out of position should it become detached 10 from the plate A. The front plate A may be formed with a hook J to connect with the loop of the other part of the belt clasp.

Referring now to Figs. 4 and 5, which illustrate a modified form of clip member 15 G, the member illustrated in Fig. 5 being formed from a sheet-metal blank. The spring arms G^1 are bent at G^2 to form a recess G^3 adapted to receive the shank F of the button and to prevent the shank from 20 turning when gripped by the arms. This construction of spring is employed in combination with a front plate having a circular central opening K therein through which the shank of the button passes and it will 25 be understood upon reference to Fig. 4 that the button is prevented from turning by the recesses G^3 formed in the clip member G.

It will be understood without further description that my invention can be equally 30 well applied to fixing buttons on brooches, hat pin heads, tobacco boxes, cigar ash trays, paper knife handles, swagger cane heads or other souvenir articles, in a similar manner to that above described in relation to waist 35 belt clasps.

If desired without departing from the spirit of my invention the spring clips may consist of a pair of resilient wires, extending 40 parallel to the slot E and having their opposite ends soldered or otherwise fastened as at M to the rear side of the front plate A. The clips constituted by these wires will

be stiffer than in the springs where the ends are free thereby enabling the sides of the shank of the button to be clipped as effectively. 45

What I claim is as follows:—

1. Means for fixing buttons to belt clasps or other articles of the kind herein referred to, comprising in combination a front plate 50 or mount having a recess adapted to receive a button, a slot in the recessed portion of the plate adapted to receive the shank of the button, a cover or back plate secured to the front plate and having a domed central portion to accommodate the shank, and a clip member located between the plates and consisting of a strand of wire bent to present portions intersecting the said slot and adapted to grip the shank of a button inserted 55 through the slot.

2. Means for fixing buttons to belt clasps or other articles of the kind herein referred to, comprising in combination a front plate 60 or mount having a recess adapted to receive a button, a slot in the recessed portion of the plate adapted to receive the shank of the button, a cover or back plate secured to the front plate and having a domed central portion to accommodate the shank, and a clip member located between the plates and consisting of a strand of wire bent to present 65 portions intersecting the said slot, such portions being recessed and adapted to partially encircle and grip the shank of a button inserted 70 through the slot.

In testimony whereof I have signed my name to this specification in the presence of two witnesses.

WALTER FRANCIS GAUNT.
